UNITED STATES PATENT OFFICE.

HUGH STUART, OF GRANITE CITY, ILLINOIS, ASSIGNEE TO COMMONWEALTH STEEL COMPANY, OF GRANITE CITY, ILLINOIS, A CORPORATION OF NEW JERSEY.

MOLDER'S CHAPLET.

Application filed June 25, 1927 Serial No. 291,336.

My invention relates to the art of casting metal and consists in an improved molder's chaplet for use in the usual manner.

The ordinary chaplet, provided with a stem 5 or shank and core and mold engaging plates, is not always satisfactory for the reason that the molten metal, when cooling, shrinks away from the chaplet shank, leaving a crevice which may extend the full length of the 10 shank and around the plates on the end of the shank. Ordinarily the presence of such a crevice is not objectionable but where the web of the casting surrounding the chaplet is required to be water-tight, leakage through a 15 crevice about the chaplet is highly objectionable.

The object of my invention is to provide a chaplet which will eliminate the possibility of such leaks.

20 In the accompanying drawings which illustrate my invention—

Figure 1 is a side elevation of one form of my improved chaplet.

Figure 2 is a top view of the same.

25 Figure 3 is a side elevation of a modified form of my invention.

Figure 4 is a transverse section on an enlarged scale through another form of my invention and showing the chaplet in the mold 30 and surrounded by the metal which has been poured into the mold.

The chaplet shown in Figure 1 comprises a stem or shank 1, a top plate 2, and a bottom plate 3, the shank being riveted to the plates as indicated at 4 or otherwise secured thereto. Intermediate the ends of the shank the same is provided with one or more radially extending ribs or fins 5 which project a substantial 35 distance from the shank.

40 The plates 2 and 3 are positioned relatively to each other so that their corners are disaligned whereby the chaplet may be readily nailed to the adjacent portions of the mold or core. This particular feature is not new with 45 me, being shown and described in Swanson Patent No. 1,160,785.

The fins 5 are of such diameter and thinness that molten metal flowing into the mold and surrounding the shank of the chaplet will 50 flow over the fins between their peripheries and the shank to such an extent that irrespective of any shrinkage which takes place in the cooling metal one or more of the fins will be gripped and partially melted by the molten

metal and a tight joint thereby formed between the chaplet shank and the cast metal. 55

In the modification illustrated in Figure 3, I show the joint forming elements as comprising a screw thread 6 forming approximately two complete turns about the shank 7 60 and spaced from the top and bottom plates 8 and 9.

In the construction shown in Figure 4, the fins 10 are tapered toward their outer peripheries as indicated at 11 and the thinner edge 65 thus provided on the fins more certainly insures the melting of a portion of the fins when the molten metal flows around the same whereby the metal of the fin and casting will merge together. Such melting action is indicated at 17 where portions of the fins have 70 been absorbed by the casting metal 16. In this figure the bottom plate 12 is shown as resting upon a portion 13 of a mold and the top plate 14 is shown as supporting a core 15 75 and the space between the mold 13 and the core 15 is shown as filled with the metal 16 and although shrinkage of the metal from the chaplet shank and plates is indicated, it will be noted that the wall formed by the 80 casting is fluid-tight because of the joint or joints formed by the fins 10.

I have found my chaplet particularly useful in casting locomotive tender underframes in which webs of the underframe casting are 85 utilized to form portions of the water tank structure. The chaplet would be of similar value in engine castings having core-formed walls which should be tight enough to prevent any escape of gas or steam. 90

Obviously, the number of fins may be reduced or increased and the particular size and shape of the fins may be varied according to the size of the chaplet, the qualities of the metal being cast, and other conditions affecting the functioning of the chaplet as described. 95

I contemplate the exclusive use of all such modifications of my invention as come within the scope of my claims. 100

I claim:

1. In a molder's chaplet, a core-supporting shank, core or mold engaging heads on said shank, and a radial fin on said shank between said heads, said shank comprising a continuous solid section of substantial thickness between said heads to firmly support the core throughout a casting operation, and said fin 105

being of substantially larger diameter than said shank and the outer portion of said fin being much thinner than said shank or the inner portion of said fin so that said outer portion will be melted by the heat of the molten metal poured into the mold during the casting operation and unite with the casting metal to form a fluid-tight joint with the chaplet before any similar melting of said shank occurs and irrespective of shrinkage of the cast metal away from said shank upon cooling of the casting.

2. In a molder's chaplet, a core-supporting shank, core or mold engaging heads on said shank, and a plurality of radial fins on said shank between said heads and spaced therefrom and from each other, said shank com-

prising a continuous solid section of substantial thickness between said heads and each of said fins being of substantially larger diameter than said shank, the outer portions of said fins being much thinner than said shank or the inner portions of said fins so that said outer portions of said fins will be melted by the heat of the molten metal poured into the mold during the casting operation and unite with the casting metal to form a series of fluid-tight joints with the chaplet before any similar melting of said shank occurs and irrespective of shrinkage of the cast metal away from said shank upon cooling of the casting.

In testimony whereof I hereunto affix my signature this 18th day of June, 1927.

HUGH STUART.
